(Cl. D13—1)

To all whom it may concern:

Be it known that we, Nelson D. Gustin, Earl W. Hartung, and Monroe A. Selo, have invented a certain new, original, and ornamental Design for a Drive-In Restaurant or the like, of which the following is a specification, reference being had to the accompanying drawing, forming a part thereof.

Fig. 2 is a side elevation of Fig. 1;

Fig. 3 is a rear elevation; and

Fig. 4 is a side elevation taken from the opposite of Fig. 2.

We claim:

The ornamental design for a drive-in restaurant or the like, substantially as shown.

NELSON D. GUSTIN.
EARL W. HARTUNG.
MONROE A. SELO.
